CODING DEVICE

Sidney L. Neff, Salt Lake City, Utah

Application January 9, 1951, Serial No. 205,114

8 Claims. (Cl. 35—3)

1

This invention relates to coding devices, by the use of which messages may be quickly and conveniently converted to code form, and thereafter, when desired, may be quickly and conveniently translated back to the original.

It is customary for governments, businesses, and other institutions, as well as for certain individuals, to transmit confidential messages to others in the form of secret code. This is particularly true in instances of messages transmitted or recorded in writing, especially during wartime.

Various devices have heretofore been developed for either placing a message in secret code as it is being written, or for aiding a person to write or transmit a message in secret code. The former are usually key-operated machines; the latter are most often devices which embody the alphabet, numbers, and other characters used in formulating a message, in suitable correlation with similar or other characters used for code purposes, to the end that a person may visually substitute a different character for that normally used in spelling out a message. The device of the invention is of this latter type.

An object of the invention is to provide a device of the type concerned wherein there is no set or predetermined relationship between the normally used characters and the code characters or abracadabra, and wherein the relationship between the two may be easily altered and retained securely in the altered position, thereby affording an extremely wide range of different codes in which a message may be put by the use of a single compact and simple mechanism.

Another object is to provide, in the device, a plurality of possible code characters for each normal character, so that the user may select at random which he will use, and thereby produce a coded message which conforms to no set pattern.

I prefer to construct the device of cylindrical elements, having approximately uniform diameter and carrying the characters concerned on their respective outside circumferential rims. These elements are mounted in side-by-side relationship on a common longitudinal axis, so they may be easily compared visually. Other elements, presenting what are essentially endless band circumferential surfaces carrying endless series of characters, may be employed, however, within the purview of the invention, for it is the manner in which such elements are associated and mounted relative to one another which make possible the new results of the invention.

2

A feature of the invention resides in the fact that the element which carries the normal characters is fixed against travel about the common axis or axes, as the case may be, while those which carry the code characters are mounted for individual travel about said axis or axes. Means, such as one or more knurled thumb nuts threaded on an axis shaft, are provided for temporarily clamping or otherwise locking the movable elements against the stationary element to preclude travel relative to one another and to the stationary element, thereby enabling the device to be set by the user for visually giving an axially extending series of code characters for each normal character.

Another feature is that the code characters of any given series are different from those of any other series.

In the use of the device, selection by the user of various ones of the possible code characters from that axially extending series which corresponds to a particular normal character, as the latter is repeated during the course of a message, makes possible the coding of such message without repeating—or at least without always using—the same code character for a particular normal character. Thus, in effect, each setting of the device gives a code having no pre-established formation. This makes breaking of the code virtually impossible.

Furthermore, rotation of one or more of the rotatable elements between the times of coding individual messages, and re-locking the device in the new setting, means that no two messages need be coded in the same code. The more rotatable cylindrical elements there are and the more side-by-side, circumferential series of code characters there are on these rotatable elements, the greater the number of different codes, and of differences within the individual codes, possible from a particular device.

An optional feature of the invention is the provision, in combination with the above, of one or more movable elements which are not locked against movement when the other elements are locked, thereby supplying auxiliary coding possibilities for the device. This is made possible by a unique mounting arrangement correlated structurally with the arrangement referred to above.

Further objects and features of the invention will become apparent from the following detailed description of the particular preferred form illustrated in the accompanying drawing.

In the drawing:

Fig. 1 represents a front elevation of the particular preferred form of the device;

Fig. 2, an end elevation looking from the left in Fig. 1;

Fig. 3, a central vertical section taken primarily but not entirely on the line 3—3 of Fig. 2;

Fig. 4, a transverse vertical section taken on the line 4—4 of Fig. 1;

Fig. 5, a similar section taken on the line 5—5 of Fig. 1; and

Fig. 6, a similar section taken on the line 6—6 of Fig. 3.

Referring to the drawing: the device illustrated comprises a plurality of cylindrical elements of approximately the same outside diameter mounted side-by-side on a common longitudinal axis.

One of the cylindrical elements, here indicated 10, is fixed by any suitable means, for example integrally, to an axially extending shaft 11, intermediate the length thereof in this instance, so that shaft portions project at opposite sides for rotatably receiving other cylindrical elements.

Rotatably mounted on the shaft portion at one side of the stationary element 10, are, in this particular instance, two cylindrical elements 12 and 13, the element 12 having several times the breadth of the element 13, which latter element has the same breadth as the stationary element 10, a breadth accommodating a single circumferential series of characters.

Rotatably mounted on the shaft portion which extends from the opposite side of the fixed element 10 are other cylindrical elements 14, 15, 16 and 17. In this instance, the elements 14 and 15 are mounted directly on the shaft 11, the element 14 being similar to the element 13, but the element 15 being of greater breadth. The elements 16 and 17 are rotatably mounted on a sleeve 18, which extends from a knurled thumb nut 19, and is concentric with and closely encircles one end of the shaft 11. Such shaft end is threaded, and the thumb nut fits over and screws onto it, serving to clamp the two rotatable elements 14 and 15 against the stationary element 10, in any given set position, when tightened, thereby locking such rotatable elements in set position without affecting rotatability of the cylindrical elements 16 and 17. In the illustrated instance, the elements 16 and 17 are rigidly joined together by means of screws 20.

A knurled thumb nut 21, similar in nature to the thumb nut 19, but without a sleeve extension, screws onto the threaded opposite end of the shaft 11, and, by bearing against the outer face of the cylindrical element 13, when tightened, locks such element 13 and its associated element 12, in any given set position, against the stationary element 10.

Thus, the stationary cylindrical element 10 serves as a reaction member against which the several normally rotatable cylindrical elements are clamped by the action of the thumb nuts 19 and 21.

The entire assembly is rotatably mounted in spaced uprights 22a of a cradle frame 22, this being conveniently accomplished by merely resting shaft portions 19a and 21a of the respective thumb nuts in receiving recesses 23 of the uprights 22a.

The several cylindrical elements have their outer circumferential surfaces marked with circumferential series of characters. In the illustrated instance, these are stamped directly upon the surfaces concerned. The stationary element 10 is marked with the normally used characters to be transposed into code characters. Such normally used characters are generally the letters of the alphabet and essential punctuation marks, but they also may advantageously include the numerical digits. The element 10 is preferably slightly greater in diameter than the other cylindrical elements, as shown, so as to stand out prominently in the group of elements and be easily seen as a starting point in the visual transposition of characters.

The rotatable element 12 to the left of stationary element 10, whose breadth is several times the breadth of the element 10, has its circumferential outer surface marked with several side-by-side circumferential series of mutually different code characters of any desired nature, for example those shown in Fig. 1. Thus, such code characters may be numbers, numbers primed or double primed, letters of the alphabet, and/or letters of the alphabet with suitable auxiliary markings.

The rotatable element 13, also to the left of the stationary element 10, carries a similar circumferential series of different code characters on its outer circumferential surface.

The individual code characters in the several series comprehended by the elements 10, 12 and 13 are preferably separated from the immediately adjacent characters in the same series by means of transverse lines, as illustrated, which lines are similarly spaced about the circumferences of the several elements, to the end that the device may be set with side-by-side characters and dividing lines in alignment transversely of the device to provide respective transversely extending series of code characters.

For ease in reading these transversely aligned characters, a straight edge 24 is advantageously supplied as part of the device. In the form shown, such straight edge 24 has depending legs 24a at opposite ends thereof which are pivoted to the respective uprights 22a of the frame 22 by means of a shaft 25. Thus, the straight edge 24 may be pushed back out of the way if desired, or may be placed in a useful position overhanging the rotatable group of cylindrical elements, as illustrated. For positioning such straight edge in its useful position immediately above, but out of contact with, the group of cylindrical elements, thumb nuts 19 and 21 are advantageously provided with circumferential shoulders 19b and 21b providing abutment stops for the respective legs 24a.

The rotatable element 14 to the right of stationary element 10 has its outer circumferential surface marked similarly to that of the element 13, but with different code characters, while the broader rotatable element 15 carries a similar single circumferential series of different code characters and a therewith aligned circumferential series of words, which, in this instance, are the word designation of numbers. The joined elements 16 and 17 are similarly marked, that is to say, the element 16 carries a single circumferential series of different code characters, while the element 17 carries a therewith aligned circumferential series of words, which, in this instance, are commonly used verbs, etc., and names of various things.

In the use of the device illustrated, the rotatable cylindrical elements 10, 12, 13, 14 and 15 are set in any desired position which aligns characters and character dividing lines transversely 75 of the device, whereupon the thumb nuts 19 and

21 are tightened to lock the several elements in their set position. The straight edge 24 is advantageously employed to facilitate the aligning operation. As explained hereinbefore, tightening of the thumb nuts serves to clamp the normally rotatable elements tightly against the stationary element 10, thereby precluding rotation of such cylindrical elements, except as a group in the cradle support 22. It should be noted, however, that the joined cylindrical elements 16 and 17 remain freely rotatable on their sleeve-mounting 18.

A message is spelled out in code by selecting, for each letter, word space, or other component, a particular code character from the transverse series of code characters aligned with a particular normally used character or other component. For example, with the device set as shown in Fig. 1, the words "a bad highway" may be coded in several different ways. Thus, it may become "11 V 72 V & T 98'", or it may become "X 99 Y 11' 65 40 98'", and so on through a wide variety of other combinations of code characters, the word "highway" being either indicated by the single code character 98' or by several code characters corresponding to the several letters making up the word.

In any instance, the code message has associated therewith the designation of a key, indicating how the recipient must set his device in order to properly decode the message. Such key consists of one character from each of the settable cylindrical elements, here the elements 10, 12, 13, 14 and 15, and from a single transverse series of characters. In the above examples, the key could be 11' 11" A 69' and 43", or any similar set of characters taken from other transverse series.

By merely loosening the thumb nuts 19 and 21, rotating one or more of the rotatable cylindrical elements to any desired extent, and retightening the thumb nuts 19 and 21, a new and different code arrangement having a different key designation may be obtained. It can be easily seen that the number of possible combinations is tremendous even with a limited number of code-carrying elements. When it is found desirable to change the relationship between the code characters of the element 16 and the words of element 17, these joined elements need merely be slipped off their sleeve-mounting 18, and re-set by removal and replacement of the screws 20.

Obviously, any convenient number of code-carrying elements may be incorporated in a single device. The particular combination illustrated merely exemplifies the possibilities of the invention. Furthermore, any single rotatable element might have a breadth of any desired multiple of the breadth utilized for a single circumferential series of code characters. Again, any two or more of the rotatable elements may be joined together in the manner here shown for the elements 16 and 17, if found desirable.

Whereas this invention is here illustrated and described with respect to a particular preferred form thereof, it should be understood that various changes, apart from the mere substitution of equivalents, may be made therein and various other constructions may be adopted on the basis of the teachings hereof, by those skilled in the art, without departing from the protective scope of those of the following claims which are generic to the broader inventive concepts disclosed.

I claim:

1. A coding device as described, comprising shaft means; a plurality of character-carrying elements mounted in side-by-side relationship on said shaft means, said elements being of approximately the same configuration and having endless band circumferential surfaces; means securing one of said elements in fixed position on said shaft, others of said elements being independently rotatable relative to said fixed element; means for locking said rotatable elements in selective set positions relative to said fixed element; a circumferential series of normally used characters, including at least the alphabet carried by the circumferential surface of said fixed element as a code-translating reference; and corresponding circumferential series of mutually different code characters, which differ from said normally used reference characters, similarly carried by said rotatable elements, enabling the establishment of transversely extending series of mutually different code characters circumferentially of the group of code-carrying elements and in side by side alignment with respective ones of said normally used reference characters.

2. The combination recited in claim 1, wherein one or more of the rotatable elements have circumferential surfaces which have breadths several times that of the fixed element and carry several side-by-side disposed, circumferential series of code characters.

3. A coding device, comprising a shaft; a plurality of character-carrying cylindrical elements mounted in side-by-side relationship on said shaft as an axis, said elements having approximately the same outside diameters; means securing one of said elements in fixed position on said shaft, others of said elements being independently rotatable on said shaft relative to said fixed element; locking means associated with said cylindrical elements for preventing relative movement of those which are rotatable; a circumferential series of normally used characters, including at least the alphabet carried by the circumferential surface of said fixed element as a code-translating reference; and corresponding circumferential series of mutually different code characters, which differ from said normally used reference characters, similarly carried by said rotatable elements, enabling the establishment of transversely extending series of mutually different code characters circumferentially of the group of code-carrying elements and in side by side alignment with respective ones of said normally used reference characters.

4. A coding device, comprising a shaft; a plurality of character-carrying cylindrical elements mounted in side-by-side relationship on said shaft as an axis, said elements having approximately the same outside diameter; means securing one of said elements in fixed position on said shaft intermediate the length thereof, others of said elements being independently rotatable on said shaft relative to said fixed element and at opposite sides thereof; locking nuts threaded on respective ends of said shaft for clamping said rotatable elements against said fixed element as a reaction member; a circumferential series of normally used characters, including at least the alphabet carried by the circumferential surface of said fixed element as a code-translating reference; and corresponding circumferential series of mutually different code characters, which differ from said normally used reference characters, similarly carried by said rotatable elements, en-

abling the establishment of transversely extending series of mutually different code characters circumferentially of the group of code-carrying elements and in side-by-side alignment with respective ones of said normally used reference characters.

5. The combination recited in claim 4, wherein at least one of the nuts has a sleeve extension concentrically encircling part of the adjacent length of the shaft, and one of the rotatable elements is rotatably mounted on said sleeve extension.

6. The combination recited in claim 3, wherein two or more of the rotatable elements are joined together by removable and replaceable fastening means.

7. The combination recited in claim 3, wherein the rotatable element adjoining the fixed element carries several side-by-side aligned, circumferential series of code characters, and the next adjoining rotatable element carries a single circumferential series of code characters.

8. A coding device, comprising a shaft, a plurality of character-carrying cylindrical elements mounted in side-by-side relationship on said shaft as an axis, said elements having approximately the same outside diameters; means securing one of said elements in fixed position on said shaft, others of said elements being independently rotatable on said shaft relative to said fixed element; a circumferential series of normally used characters, including at least the alphabet, carried by the circumferential surface of said fixed element as a code-translating reference; corresponding circumferential series of mutually different code characters, which differ from said normally used reference characters, similarly carried by said rotatable elements, enabling the

establishment of transversely extending series of mutually different code characters circumferentially of the group of code-carrying elements and in side-by-side alignment with respective ones of said normally used reference characters; and cradle journaling said shaft, locking means associated with said cylindrical elements for preventing relative movement of those which are rotatable, said locking means including a nut threaded on an end of the shaft, so as to bear against a rotatable cylindrical element and exert a clamping action against the fixed cylindrical element as a reaction member, said nut having a shaft portion serving as a bearing in conjunction with said cradle, the latter having an open recess for the reception of said shaft portion; a straight-edge pivotally mounted longitudinally of the device for swinging into position transversely of the group of the cylindrical elements, said straight-edge having depending legs pivoted to said cradle; and a circumferential shoulder provided by said locking nut, as an abutment stop for a leg of the straight-edge in the positioning of the latter relative to the group of cylindrical elements.
